UNITED STATES PATENT OFFICE.

THOMAS JOHN DORAN, OF NEW YORK, N. Y.

HAND-OPERATED DRILL.

SPECIFICATION forming part of Letters Patent No. 614,848, dated November 29, 1898.

Application filed February 11, 1898. Serial No. 669,919. (No model.)

To all whom it may concern:

Be it known that I, THOMAS JOHN DORAN, a citizen of the United States, residing at New York, (Brooklyn,) in the county of Kings and State of New York, have invented certain new and useful Improvements in Hand-Operated Drills, of which the following is a full and complete specification, such as will enable those skilled in the art to which it applies to make and use the same.

This invention relates to hand-operated drills, and has for its object to provide a support for such drills, which is adapted to automatically feed the drill in its work and return the same when the work of drilling is completed.

The invention consists of a supporting-frame for drills constructed substantially as hereinafter described, and defined in the claims.

The invention is fully disclosed in the following specification, of which the accompanying drawings form a part, in which the separate parts of my improvement are designated by the same letters of reference in each of the views, and in which—

Figure 1 is a front elevation of the improved supporting-frame for drills. Fig. 2 is a side view thereof, and Fig. 3 is a view of a detail.

Referring to the drawings, A represents the base or support of the improved supporting-frame for drills and is made, preferably, of metal and substantially rectangular in form. Supporting-standards A' are secured to the said base, preferably by means of screw-threads, and at a point somewhat above the center of each standard is arranged a flange a, upon which rests a helical spring B, coiled about the standards A'. The upper portion of the standards A' is provided with screw-threads upon which are mounted threaded nuts a' a'', and a helical spring B' is coiled about the standards A' between the said nuts a' a''.

A drill-supporting rod D is loosely mounted upon the standards A' and bears upon the upper ends of the springs B, and said rod is provided at its central point with a threaded opening d, which is adapted to receive a binding-bolt d'. An ordinary drill C is provided below the breastplate with slotted or diverging arms, between which the supporting-rod

D is arranged and to which the said rod is removably secured by means of the binding-bolt d', which passes transversely through the supporting-rod D and through the arms of the slotted or spread portion of an ordinary drill-stock which embraces said rod.

A pressure-bar E is loosely mounted upon the upper portion of the standards A' and normally rests upon the lower nuts a'. The lower ends of springs B' bear upon the upper face of the said bar, while the upper ends of said spring engage the under side of the upper nuts a''. By changing the position of the lower nut a' the position of the pressure-bar E may be changed, and by changing the position of the upper nut a'' the tension of the spring B' may be regulated. An adjusting-screw rod F is threaded in the pressure-bar E and is adapted to bear upon the breastplate of the drill to force the same to its work.

The lower springs B are principally for sustaining the weight of the drill and serve to retract the drill after the work of drilling is accomplished and the adjusting-rod F is disengaged from the breastplate of the drill.

The upper springs B' are the compressing-springs and are considerably stronger than the lower springs B and serve to force the pressure-bar E downwardly against the drill C.

The base A is provided upon its under side with a longitudinal bar or rib A'', by which the frame may be secured in a vise or other suitable clamp.

In Fig. 3 is illustrated a modified form of base G, in which are provided threaded sockets g and a longitudinal slot g'. The lower ends of the supporting-standards A' are adapted to be screwed into the threaded sockets g and the base clamped to a bench or other suitable support by means of a threaded bolt working in the slot g'.

The drill C is secured to the supporting-rod D and is adapted to be advanced or retracted as required. The drill is then forced to its work by turning down the adjusting-screw F, as will be evident from the above description.

Having fully described my invention, I claim as new and desire to secure by Letters Patent—

1. In a drill-supporting frame, the combination with supporting-standards, a drill-supporting rod mounted thereon and movable

with relation thereto, a pressure-bar sleeved upon said standards above the supporting-rod, means for sustaining said supporting-rod and governing the position thereof, and means 5 for operating the pressure-bar, of a drill carried by the supporting-rod and adapted to be engaged by the pressure-bar, substantially as described.

2. In a drill-supporting frame, the combination with supporting-standards, a drill-supporting rod loosely mounted thereon, sustaining-springs sleeved upon said standards upon which said rod rests, a pressure-bar loosely sleeved upon said standards, compression-springs mounted upon the standards and adapted to bear upon said pressure-bar, of a drill secured to said supporting-rod and means 15 connected with said pressure-bar adapted to engage the drill and force the same to its work, substantially as described.

3. In a drill-supporting frame, the combination with supporting-standards, threaded at their upper ends and provided with a suitable flange, sustaining-springs sleeved on said 25 standards and bearing against said lugs, an upper and a lower nut screwed upon the threaded ends of said standards, a supporting-rod loosely mounted upon the standards

and bearing against the sustaining-springs, a pressure-bar loosely sleeved upon said standards and adapted to bear upon the said lower nuts, compression-springs sleeved upon the standards and adapted to engage said pressure-bar, and an adjusting-screw rod threaded in said pressure-bar, of a drill secured to the 30 said supporting-rod and adapted to be engaged by said adjusting-screw rod, substantially as described.

4. In a drill-supporting frame, the combination with a drill of supporting-standards, sustaining-springs sleeved thereon, a supporting-rod bearing upon said spring and adapted to support said drill, a pressure-bar loosely mounted upon the said standards and adapted to engage said drill, and compression-springs of greater strength than said sustaining-springs adapted to bear upon said pressure-bar, substantially as described.

In testimony that I claim the foregoing as my invention I have signed my name, in presence of the subscribing witnesses, this 8th day of February, 1898.

THOMAS JOHN DORAN.
